CONTAINER

John Ernest Page, Sydney, New South Wales, Australia, assignor, by mesne assignments, to The Guardian Trust Company, Cleveland, Ohio, a corporation of Ohio, trustee for Gibson Patent Containers, Ltd., a corporation of New South Wales, Australia

Application December 6, 1930. Serial No. 500,493

11 Claims. (Cl. 229—5.5)

The invention relates to containers, and more particularly to a container consisting principally of paper board.

According to one form which the invention may take, the container may comprise a substantially cylindrical body of paper board and a bottom structure having a substantially plane bottom and an inwardly extending conical rim. The lower edge of the body may be provided with slits forming fingers which may be spread outwardly within the rim of the bottom structure and held in such position by a suitable insert. In this way a positive interlock is obtained between the body and the bottom structure which effectively prevents separation of these parts even when used to carry heavy articles. The container may be made substantially cylindrical or it may be of conical form, in which case the containers may be conveniently nested for shipping in assembled condition.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which

Fig. 1 represents a body blank;

Fig. 2 represents a collar blank for making up the bottom structure;

Fig. 3 indicates a circular sheet of soft material such as paper, cloth or cellophane;

Figs. 4, 5 and 6 represent discs of paper board used for making up the containers;

Fig. 7 illustrates a completed container;

Fig. 8 is a section through one corner of the container shown in Fig. 7;

Fig. 9 is a section through one corner of the bottom structure used in Fig. 7;

Fig. 10 is a body blank forming part of a conical container, such as a pail;

Fig. 11 is a side elevation of the pail; and

Fig. 12 is a detail illustrating how the bail of the pail is secured.

In the following description and in the claims parts will be identified by specific names for convenience, but they are intended to be as generic in their application to similar parts as the art will permit.

Like reference characters denote like parts in the several figures of the drawings.

In the drawings accompanying and forming part of this specification, practical commercial embodiments of the invention are shown, but as such illustrations are primarily for purposes of disclosure, it will be understood that the structures may be modified in various respects without departure from the broad spirit and scope of the invention as hereinafter defined and claimed.

Referring now to the drawings, and more particularly to Figs. 1 to 9, inclusive, the container shown in Fig. 7 is made from the blanks indicated in Figs. 1 to 6, inclusive. The body blank 20 comprises a body portion 120 slit to form a plurality of fingers at its lower edge. The body portions of the fingers are denoted by 123 and the finger ends are denoted by 23. The lines 21 and 22 indicate score lines for bending the fingers at these points, as will be hereinafter set forth more in detail.

The bottom structure may be made up from a blank 25 shown in Fig. 2 which comprises a rim forming band of paperboard, metal or other material 26. The band may be provided with fingers 27 separated from the rim portion by a score line 28. The band is cut along curved lines as indicated so that, when it is bent to form a ring with its ends riveted or otherwise secured together, the resulting rim portion will be conical.

To assemble the bottom structure as indicated in Fig. 9 the disc 29 of paper is first laid flat and the outer disc 30 is superimposed thereon. The collar 25 with its ends secured together by pasting or riveting, is placed over the disc 30 as indicated, with its fingers 27 bent inwardly. The paper or cellophane wrapper 29 is then bent over the top of the band 26, as indicated, and down inside so that it overlaps the fingers 27 at 126. The next smaller disc 31 is then forced into position shown to rigidly hold the parts of the bottom structure assembled. It will be understood that a suitable machine may be provided for assembling these parts, if desired.

To assemble the bottom structure and body, the body blank 120 is curved to form a cylinder and its meeting edges are secured together in any desired way, as by rivets 125, as indicated in Fig. 7. The lower end of the body 20 is placed within the bottom structure, which is indicated by 33, with its finger ends 23 overlying the disc 31, as indicated in Fig. 8. The insert 32, which is smaller than disc 31, is then forced into position to securely lock the body 20 and bottom structure 33 together to form the completed container.

It will be understood that the disc 31 is larger than the inside diameter of the upper edge of the band 26 so that it must be forced past this point. The paper board material permits a certain amount of yielding both in the disc 31 and in the conical band 26 so that the positioning of the disc 31 is accomplished without rupturing any of the parts. At the same time the disc 31 firmly holds the end 126 of the wrapper 29 tucked in the position shown. In a similar manner the disc 32, while larger than the inside diameter of the tubular body 120, can be forced into position firmly to hold the finger parts 23 and 123 expanded against the adjoining parts of the bottom structure or closure 33. It will be understood that, if desired, the wrapper 29 may be adhesively secured to the disc 30 and band 26.

In some cases the middle disc 31 may be omitted, in which event the inner disc 31 holds both the fingers and the wrapper in position.

If desired, the closure shown in Fig. 9 may be made one piece instead of composite, as illustrated. In other words, the closure will comprise an end wall with an in-turned side flange integral therewith, both wall and flange being made of homogeneous fibrous or metallic material. This closure may be either moulded to form the construction just described, or it may be made in the same manner as any cylindrical paper board cover. Or, if desired, the closure may comprise a band member having an upstanding rim portion and an inwardly extending lip or flange portion of relatively stiff material, upon which the disc member 31 seats, to form the bottom of the container.

Referring now to Figs. 10, 11 and 12, the container herein shown is similar to that shown in Fig. 7 except that it is made conical. The blank is denoted by 80, being cut in the shape shown so that when folded around to fasten its edges together, the shape will be conical. It is provided with finger parts 81 and 82 which cooperate with the bottom structure 84 to hold the parts in assembled relation in a manner similar to that described above in connection with Fig. 7.

If desired, the container may be provided with a bail 86 in which case a sheet metal member 85 may be conveniently secured to the body 80 for securing the bail 86 thereto.

Thus, several specific embodiments of a container according to the invention have been disclosed. These containers may be shipped wholly knocked down or wholly or partially set up. The shipper can easily set up the body portion and apply the bottom structure thereto in the manner set forth above. In the event it is desired to ship the bodies in set-up condition, the conical bodies are particularly adapted for this purpose, since they may be shipped in nested relation, one being placed within the other. The bottom structures or closures shown in Fig. 9 may, of course, be shipped either set up or knocked down.

It will be noted that the bottom structures or closures because of their manner of construction are quite rigid. When the closures are attached to the comparatively yieldable body the rigidity of such closures imparts a substantial rigidity to the entire container, thus imparting strength to the set-up container and assisting it to withstand hard usage.

It will be understood that although a round container has been disclosed for purposes of illustration, the invention is applicable also to triangular, octagonal and other shapes. Furthermore, the insert discs, as for instance the discs

30, 31 and 32, may be of other materials than paper board, as, for instance, glass or celluloid, or other transparent material.

The containers above described are strong and durable and will carry heavy loads without weakening. They are also cheap, principally because they are made of paper board and are easily assembled or set up by the maker or shipper. They are particularly well adapted for shipping large heavy contents in either solid or semi-solid condition. These containers may also be used for shipping coffee, cereal, crackers, hats, millinery, artificial flowers, cement, sugar, salt, cocoa and other contents. After material has been packed therein, the outward pressure thereby exerted on the side walls of the container maintains the fingers 123 bulged outwardly against the rim portion of the closure, and the insert disc 32 is then not further needed. If the container is packed while resting on its bottom closure the insert disc 32 may be entirely eliminated when certain kinds of material, which are hard, are packed therein.

While certain novel features of the invention have been shown and described and are pointed out in the annexed claims, it will be understood that various omissions, substitutions and changes may be made by those skilled in the art without departing from the spirit of the invention.

What is claimed is:

1. In a container, a tubular body of paper board having its end slit at circumferentially spaced points to provide a plurality of fingers, said fingers being scored at their junctions with the body, said fingers being scored also part way their length to form inner and outer finger parts, a closure comprising an end wall and an inwardly extending conical side flange, said fingers being positioned within said closure with their outer parts against said bottom wall and their inner parts against said side flange, and a disc insert engaging said fingers at the junction of their inner and outer parts to hold said fingers in expanded position firmly against said side flange and end wall.

2. A container for packaging ice cream comprising a body having an expandable outwardly flared attaching portion and an inturned portion at one end thereof, a closure comprising a conically shaped rim, said attaching portion being disposed within said closure, and means positioned within said container for holding said attaching portion in contact with said rim.

3. In a container, a body having a side wall with fingers at its end, a closure comprising an end wall and an inwardly projecting side wall surrounding said fingers, and an insert to hold said fingers within and against the side wall of said closure.

4. In a container, a wall portion having an outwardly flared part and an inwardly extending part at an end thereof, a conically shaped second wall portion surrounding said end of the first wall portion, and means including an inserted member for holding said outwardly flared part of the first wall portion positioned against said second wall portion.

5. In a container of the class described, the combination of a tubular body and a bottom closure for said body comprising a conical sleeve surrounding the bottom marginal portion of said body, a part carried by and extending laterally inwardly from the bottom edge of said sleeve, an end member seated on said inwardly extending part to form the bottom of the container, and

- an insert plate of larger size than the interior size of said tubular body, said insert plate being adapted to be forced into position inside of said body and within said sleeve to thereby expand 5 said bottom marginal portion of the body into locking engagement with said sleeve.
6. In a collapsible container of the class described, the combination of a tubular body provided with a flexible outwardly expandable portion 10 at its lower end, and a bottom closure for said body comprising a sleeve surrounding the expandable portion of said body, an upper portion of said sleeve substantially fitting the body and a lower portion of said sleeve being enlarged relative to the normal size of the body, a part carried 15 by and extending laterally inwardly from the bottom edge of said sleeve, and a bottom plate of larger size than the interior size of said tubular body, said bottom plate being adapted to be forced into position inside of said body and within the enlarged lower portion of said sleeve to thereby expand said bottom marginal portion of the body into interlocked relation with said sleeve, the latter having a laterally inwardly-extending bottom 20 part constituting a seat for said plate within said enlarged sleeve portion.
7. In a set-up container of the class described, the combination of a tubular body slit to provide an expandable portion at its lower end, and a bottom closure for said body comprising a frusto-conical sleeve surrounding the lower marginal portion of the body, a part carried by and extending laterally inwardly from the bottom edge of the sleeve, and a bottom plate of larger size 25 than the interior size of said body, said plate being adapted to be forced into position inside of said body and within the base portion of said conical sleeve to thereby expand the lower marginal portion of the body into conformity with said 30 sleeve.
8. In a set-up container of the class described, the combination of a tubular body of paper hav- 35
- ing its lower marginal portion slit at circumferentially spaced points to provide a plurality of tongues at the bottom end of said body, and a bottom closure for said body comprising a sleeve surrounding said slit portion of the body, an upper portion of said sleeve substantially fitting the body and a lower portion being enlarged relative to the normal size of the body, and a bottom plate of larger size than the interior size of said tubular body, said bottom plate being adapted to be forced into position inside of said body and within said sleeve to thereby expand said slit portion of the body into interlocked relation with said sleeve, the latter having a laterally inwardly-extending part at its bottom edge constituting a stop for positioning said plate within said tongues. 40
9. A container for ice cream comprising, a body having a side wall with a flexible and outwardly deformable portion and an inturned portion at its end, a non-yielding closure comprising an end wall and an inwardly projecting side wall surrounding said deformable portion, and an insert to hold said deformable portion within and against said side walls. 45
10. In a container, a body of fibrous material having a side wall with fingers at one end thereof, a closure having an inwardly projecting annular side flange and an end wall forming the end of the container, and a disc insert holding said fingers firmly against said side flange and between said end wall and itself. 50
11. A collapsible ice cream container comprising, a tubular member having slits therein to provide an outwardly expandable end portion, a closure member telescoped over said end portion, said closure member having a rim portion tapered inwardly, and means holding said expandable end portion pressed in locking engagement against said tapered portion. 55
